UNITED STATES PATENT OFFICE

2,076,076

BULLETPROOF VEST

Alexander H. Duniap, Chicago, Ill.

Application June 7, 1934, Serial No. 729,398

2 Claims. (Cl. 89—36)

The invention in the present instance, relates generally to an armor for the body, but more particularly to an armor or bullet proof vest which is primarily adapted for the use of protecting policemen, bank messengers, watchmen and such other individuals. It has long been the practice heretofore in the construction of vests of this type to completely envelope the armor plates in separate pockets or envelopes with each envelope and plate overlapping the adjacent envelope and armor plate. With this arrangement, it is necessary to interpose a cloth or fabric between the adjacent overlapping plate which as a matter of fact, has a tendency to separate the adjacent overlapping armor plates so that in some instances bullets are ricocheted or deflected between the adjacent overlapped armor plates, resulting in the bodily injury to the wearer. It is therefore, the primary object of the present invention to overcome this difficulty and provide a novel and improved construction and arrangement in which the overlapped armor plates, in effect, positively contact one another so as to form in effect a complete metal shield over these overlapped plates without losing the flexibility essential to the wearer.

Another object of the invention is to provide a novel and improved bullet proof vest which is not only efficient, but is also an improvement upon the vests of former constructions, in that, it is relatively lighter in weight and does not shock or bruise the body when hit by bullets. In general, my improved bullet proof vest consists of a series of vertically extending spring steel strips which overlap each other in shingle like arrangement with the major part of their overlapping portions held in contacting relation. The opposite ends of the steel strips are seated or secured in relatively short recesses in the supporting structure so as to prevent their dislodgment and maintain them in their contacting relationship. This contacting relation of the overlapping steel plates affords not only sufficient flexibility to the wearer, but also prevents a separation of the adjacent plates with respect to each other and thereby prevents the possibility of the bullet being deflected or ricocheted between the overlapped adjacent plates.

A still further object of the invention is to provide a novel and improved bullet proof vest in which the overlapped contacting adjacent plates are further held in contacting relationship by a strip of adhesive material extending across the intermediate or center portion of all of the plates.

55 A further object of the invention is to provide

a bullet proof vest which is of new and improved construction, is light and comfortable when worn and may be manufactured at comparatively reasonable cost.

A still further object of the invention is to provide a novel and improved bullet proof vest construction in which the side portions of the vest may be detachably fastened to the back and front so as to form in effect one integral vest, or may be, when detached, used separately.

These and other objects are accomplished by providing a construction and arrangement of the various parts in the manner hereinafter described and particularly pointed out in the appended claims.

Referring to the drawing:

Fig. 1 is a perspective view of a more or less conventional form of vest having my improved construction embodied therein;

Fig. 2 is a perspective view of the detached bullet proof armor which embraces the sides of the wearer;

Fig. 3 is a front elevational view of the front portion of the vest with certain parts broken away to illustrate the construction;

Fig. 4 is an enlarged fragmentary view showing the manner in which the ends of the armor plates are secured in their overlapped position;

Fig. 5 is a cross sectional view taken on the line 5—5 in Fig. 4;

Fig. 6 is a cross sectional view taken on the line 6—6 in Fig. 4; and

Fig. 7 is a diagrammatic view showing the manner in which the respective sections of the vest overhang the body of the wearer.

In illustrating one form of my invention, I have shown the same in connection with the conventional form of vest, generally indicated by the reference character 10, which comprises a front portion 11, detachably connected as shown at 12 to a rear portion 13. The side portions, generally indicated by the reference character 14, may be attached by snap buttons 15 and 16 so that the complete vest in effect may be one integral part or the side sections may be detached from the vest proper, as clearly shown in Figs. 1 and 2 of the drawing. The front portion of the bullet proof vest comprises three separate sections, generally indicated by the reference characters 17, 18 and 19 while the rear portion of the vest proper comprises one single elongated section generally indicated by the reference character 20. The side sections shown in Fig. 2 are similarly provided with armor portions on

the sides thereof covering the space between the front and rear sections of the vest proper.

The essential feature of the present invention involves a novel arrangement in which the overlapping adjacent spring plates contact substantially throughout their length while the ends of the plates are seated in overlapping recesses for securing the armor plates in relatively fixed flexible positions with respect to each other. The construction of all of these sections are essentially identical and comprise a main covering 21 which is preferably made of imitation leather or other suitable material. Secured to the upper and lower edges of the main covering 21 is a strip 15 of material generally indicated by the reference character 22. The material 22 is stitched vertically as shown at 23 and 24 so as to form in effect recesses 25 in which the ends of the spring steel armor plates 26 are inserted. The lower edge of 20 the lower strip 22 is of course, suitably stitched, as shown at 27, to the covering 21 while the upper edge of the top strip 22 is similarly stitched, as shown at 28, for preventing displacement of the armor plates 26 from their respective overlapping 25 position, as clearly shown in Figs. 3, 4 and 5 of the drawing.

With this arrangement, it will be noted that the spring steel armor plates, particularly the adjacent overlapping ones, contact, as shown at 30 28', substantially throughout their entire length with the exception of the end portions which extend into the recesses. This arrangement of having these plates contact, prevents any possibility of the bullets penetrating at this point, which 35 sometimes happens in connection with bullet proof vests heretofore used where the material separates the plate at this point.

In order to further insure contacting relationship of the overlapping steel plates, I find it highly desirable to extend a strip of surgeon's tape as shown at 29, on one side or both sides of the plate at a position substantially the center thereof as clearly shown in Fig. 3. This arrangement further insures the contacting relationship of the 45 overlapping plates and precludes any possibility of the bullets penetrating at this point.

From the above description, it will be readily seen that I have not only provided a simple, efficient and easily manufactured bullet proof vest, but one that has the advantages of securing a contacting relationship of the adjacent overlapped spring steel armor plates, thereby eliminating any possibility of entrance of the bullet between these plates by reason of their separation such as has been experienced by the bullet proof vests heretofore constructed.

While in the above specification I have described one embodiment which my invention may assume in practice, it will of course, be understood that the same is capable of modification and that modification may be made without departing from the spirit and scope of the invention as expressed in the following claims:

What I claim as my invention and desire to secure by Letters Patent is:

1. A bullet proof vest comprising a supporting structure, armor sections flexibly connected to said structure, sections consisting of a supporting member, separate fabric strips positioned adjacent the opposite ends of said member forming overlapping recesses, a plurality of sets of armor plates having their ends engaged in said recesses, each set of plates overlapping the next adjacent set and a covering embracing said armor plates tightly whereby the overlapped portions of said plates contact the adjacent plates substantially throughout their length.

2. A bullet proof vest comprising a supporting structure, armor sections flexibly connected to said structure, said sections consisting of a supporting member, separate fabric strips positioned adjacent the opposite ends of said members forming overlapping recesses, and a plurality of armor plates having their ends solely engaged in said recesses, certain of said overlapping plates flexed into contacting relationship with the next adjacent plate so as to contact substantially throughout their entire length for preventing an opening therebetween.

ALEXANDER H. DUNLAP. 45
